UNITED STATES PATENT OFFICE.

WILLIAM WALTER OWEN, OF OAK PARK, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed May 20, 1918, Serial No. 235,452. Renewed January 22, 1923.

To all whom it may concern:

Be it known that I, WILLIAM WALTER OWEN, a citizen of the United States of America, and a resident of Oak Park, Cook County, and State of Illinois, have invented certain new and useful Improvements in Automatic Telephone Systems, of which the following is a specification.

My invention relates in general to an automatic telephone system in which connections are controlled automatically by the use of so called automatic switches.

One of the main difficulties which has been encountered by the use of automatic systems, especially in larger cities, is the large number of digits in a called number, that is, in order to set up a call a subscriber is often required to operate his calling device as many as eight times to send the required 20 digits, and if branch exchanges are used even more digits may be required. Although certain switches have been devised which take 20 or more steps to give them access to more lines, this sort of a switch requires 25 too great an amount of time for its operation and requires a complicated and more or less clumsy dial. Also although such switches require less operations, yet the numbers still remain complicated because 30 each character may have two digits, as 20, or 32, or some thing similar.

Among the objects of my invention therefore, is to provide an improved system of standard construction which practically cuts in half the number of digits of a called number while at the same time it creates a material decrease in the amount of switching mechanism required. Thus my invention will be seen to be of considerable importance 35 in the art, as it overcomes the two greatest difficulties encountered, namely, initial cost of installation and the operations required of a subscriber or operator. My system would be especially valuable in the installation of a large automatic system of, say a million lines, which it has been thought impractical to install with the present type of equipment. Other objects of my invention are to provide a novel and improved calling 40 device for such a system and to provide improved automatic switches and circuits for use with such a dial to accomplish the desired results, and also to adapt said circuits

as nearly as possible to a standard type of switching mechanism.

In the drawings Figs. 1 and 2 show a calling line A (Fig. 1), provided with a dial such as is shown in Fig. 3, and having a line switch C individual thereto. The substation A is of the well known common battery type of substation and the line switch C is of a well known type of rotary line switch whose wipers stand when idle upon the trunk line last used. The line switches C have access to a number of selectors D which are of the well known Keith-Erickson type of selector switch which is controlled by impulses over two sides of a line in series to step its wipers in a vertical direction from one to ten steps and then rotates ten or more steps to select idle trunk lines, the number of trunk lines in a level depending upon traffic conditions and grouping. The circuits of this selector have been slightly changed to adapt it to operate in a system embodying my invention. The main difference, however, between this selector and the standard type is that the shaft has been elongated and carries three sets of wipers, two line wipers and one private wiper in each set. Each wiper has a separate bank of one hundred or more contacts associated therewith and when the switch is operated all the wipers move together to corresponding contacts of their respective banks. Means are provided to switch the line circuit leading through this selector to any one of the three sets of wipers which means are controlled by certain springs at the substation for either grounding one side of the line to pull up a differential relay, or for including a high resistance in the line circuit to cause a marginal relay to fall back. These springs are closed automatically by a subscriber just before the impulses of a digit are sent and are controlled by the improved dial as shown in Figure 3.

This dial may be of any well known type which operates to open a line circuit to send from one to ten impulses thereover except that the front plate or finger hole dial has been enlarged and three concentric rows of finger holes provided instead of one row. The inner row of finger holes are as usual and are designated by the numerals one to

ten respectively. The second row of finger holes have the same relation as the inner row to the operating mechanism of the dial except that they are designated by the letters A—K respectively, and, in addition, when a finger is inserted into any one of the finger holes A—K and the dial is rotated around to the finger stop, the springs 2 and 3 will be operated momentarily to ground one side of the line circuit as shown in Fig. 1 at the substation A, to cause a differential relay in the selector or connector to pull up and switch the line circuit to the second set of wipers. The outer row of finger holes also bear the same relation to the operating mechanism as the inner row of holes except that these holes are designated by the letters L—W respectively, and control another pair of springs 4 and 5, which, as shown at substation A, include a high resistance in the line circuit to allow a marginal relay in the selector or connector to fall back, whereby the line circuit is switched to the third set of wipers. It will be seen therefore, that no matter which dial or row of finger holes is used no more than ten impulses is transmitted. That is, if a subscriber calls 2, two impulses will be delivered in the usual manner; if B is dialed, then two impulses will also be sent except that springs 2 and 3 will be closed momentarily just before the impulses are sent; if M is dialed, two impulses will also be sent except that the springs 4 and 5 will be momentarily closed just before the digit. The springs 2 and 3 and the springs 4 and 5 are therefore similar to push buttons operated just before sending a digit to switch to desired set of wipers except that they are automatically controlled without the knowledge of the calling subscriber. These springs 2 and 3 and 4 and 5 may be controlled in any desired mechanical manner if desired instead of by the finger of the calling party. It will be seen therefore that if the letter A or any of the second row holes are dialed the connection will be extended by the selectors or connectors through their second set of wipers to some contact of the second banks and if the letter L or any of its series are dialed, the call will extend through the upper wipers and through contacts of the third or upper banks.

I have shown a trunk line leading from each of the three banks of the selector D, it being understood that each set of wipers has access to one hundred or more of such trunk lines and that the trunks from each bank may lead to separate exchanges, or simply to other groups of connectors. The trunk line leading from the contact of the lower banks is shown as leading to the connector switch H (Fig. 2) which has access to the subscribers of one 300 group.

The connector H is of standard two wire

type except that certain relays have been added as in the selector which are controlled by the springs 2, 3 and 4, 5 of my special calling device to switch the line circuits to either of the three sets of wipers shown. 70 This connector is provided with an elongated shaft as is the selector and with three sets of contact banks of one hundred lines each so that the connector may pick out a called subscriber's line in either of the 75 groups or of 300 lines.

I will now describe the operation of the system in detail, reference being had to the drawings. When a subscriber at substation A desires to call a subscriber whose line is connected to the second contact in the second level of the lower bank of the connector (for instance) then the digit dialed will be 222 as is usual to the now existing systems. 85 In this case the operation of the switches will not be changed and the call will be set up in a well known manner of which I will give a general description only. When the subscriber A removes his receiver the line circuit is closed to energize the line relay 6 of the line switch C. Relay 6, upon energizing, closes a series circuit for the switching relay 7 and the rotary magnet 8 in series. In passing over busy trunk lines relay 7 is short circuited by ground on the 95 private wiper which connects said ground direct to rotary magnet 8 through springs 9 and 10. When an idle trunk is reached relay 7 is no longer shorted and energizes in series with the rotary magnet, which does not energize at this time due to the comparatively high resistance of relay 7. As soon as relay 7 energizes the line circuit of substation A is extended through the front contacts of relay 7 and the line wipers 11 and 12 to the selector D. This extension of the line circuit causes the line relay 12 of selector D to energize in series with substation line A and relays 13 and 14. Relay 13 is a marginal relay but energizes in this circuit to open its springs while relay 14 which is differential does not energize as its windings oppose each other. Now, as the first digit 2 is dialed the line circuit is opened twice to cause relay 12 to send two impulses to the vertical magnet 15 while holding the release relay 16 energized. Relay 17 is held energized during this digit as it is in series with vertical magnet 15. Although marginal relay 13 also responds to this series of impulses its energization has no effect as its control circuit to relay 30 is opened at the first vertical step by off normal springs 40. Relay 17 while energized closes a circuit for the rotary interrupter relay 18 125 which in turn prepares a circuit at springs 19 for the rotary magnet 20. After the impulses to the vertical magnet cease, relay 17 falls back and completes the circuit of the rotary magnet which energizes to step the 130

wipers 21—29 onto the first contacts of their respective banks. Only the wipers 21, 22 and 23 are effective at this time as neither of the relays 30 or 31 are energized. The rotary magnet upon energizing opens the initial circuit of the relay 18 at springs 32 and upon again deenergizing closes a new circuit for said relay 18 to the test wiper 23. The ground on busy contacts now controls the relay 18 to operate the rotary magnet to step the wipers to an idle trunk line in the second level of the lower line bank. As soon as such idle trunk line is found, relay 33, which has been short circuited during rotation by the ground on the test wiper, energizes in series with the rotary interrupter relay 18, which, being of comparatively low resistance, does not energize at this time. Relay 33, upon energizing, disconnects the relays of the selector D from the line circuit and extends it through the wipers 21 and 22 to the selected trunk line, which it will be assumed, leads to the connector switch H (Fig. 2). A circuit is closed at this time for the line relay 34 of connector H in series with the extended line circuit and with the two special relays 35 and 36. Relay 35 being marginal energizes and relay 36 being differential does not energize. These relays are similar to relays 13 and 14 of selector D, and have no effect at this time. Relay 34 energizes, however, and closes the circuit of release relay 37 at its front contact. Relay 37 also energizes to prepare a circuit for relay 38 and vertical magnet 39 and to ground the release trunk at its upper springs to hold relays 33 and 7 of the preceding switches energized.

The next digit 2 will now be sent by the calling subscriber, using as before the second finger hole of the inner row which is marked 2. In this case as before springs 2 and 3 and 4 and 5 are not affected and the switch operates as usual under the control of the line relay. Relay 34 responds to these two impulses to operate the vertical magnet 39 in series with relay 38 to step the wipers 41—49 inclusive up to the second level in their respective banks. The initial energizing circuit of magnet 39 and relay 38 extends from ground through spring 52 and its back contact, springs 53, springs 54, and relay 38 and magnet 39 to battery. As soon as the switch takes its first vertical step the springs 54 are opened and springs 55 are closed, thereby providing a new energizing circuit through springs 55 and spring 56 and its front contact, relays 37 and 38 being held energized during impulses.

As soon as the impulses for this digit cease relay 38 falls back to prepare a circuit at spring 56 and its back contact for slow relay 57 and magnet 58. The subscriber now operates the dial for the last digit 2 in the same manner as before to again operate re-

lay 34. In this instance the relay 34 operates to control relay 57 and magnet 58 over a circuit from ground through spring 52 and its back contact, springs 53, springs 55, spring 56 and its back contact, springs 59, relay 57 to battery, and springs 60 and magnet 58 to battery. Magnet 58 operates to step the wipers 41—49 around to the second contacts in their respective banks. It is understood that only the wiper set 41, 42 and 43 is effective at this time, due to the normal condition of relays 50 and 51. Relay 57 holds energized during rotation and for a second thereafter to connect the busy test relay 61 to the effective private wiper 43. Only one line will be tested of course, although each set of line and private wipers rests in engagement with a subscriber's line and test conductor. If the called line is busy a ground will be present on its test contact which will pass over private wiper 43, through springs 62 and 63 and their bank contacts, springs 64 and 65, and relay 61 to battery. Relay 61 operates over this circuit, locks itself as soon as relay 57 falls back, opens the circuits of the wiper cut on relay 66 and the operating magnet, and connects busy tone current from the machine M to the calling line, whereupon the connection will be released in the usual manner by the calling subscriber opening the line circuit.

If the called line is found idle, no circuit will be closed for the busy relay 61, and as soon as relay 57 falls back, a circuit will be closed for the wiper cut on relay 66 from ground through the upper springs of relay 37, springs 68, lower winding of relay 66, springs 69 and 64, springs 63 and 62 and their back contacts, wiper 43, and through the bridge cut off relay of the called man's line switch to battery. Relay 66, upon energizing locks itself energized through its upper winding, connects ground direct to wiper 43, opens the rotary magnet circuit, and connects the ringing generator to the called line through springs 70 and 71. The circuit for signaling the called subscriber extends as usual from battery through the upper winding of relay 67, spring 72 and its back contact, springs 70, springs 73 and 74 and their back contacts, wiper 41, to and through the ringing equipment of the called station, back through wiper 42, springs 75 and 76 and their back contacts, springs 71, spring 77 and its back contact, to armature 78 of ringing interrupter relay R, which relay alternately connects generator and the booster battery to this signaling circuit to signal the called subscriber. As soon as the called subscriber answers, relay 67 is energized to disconnect the signaling circuit and connect the called line to the windings of relay 79, which relay energizes in series with the called line to reverse the

connections of the line relay 34 to the line circuit, whereby battery is reversed to the calling line for any desired purpose such as metering. The two subscribers may now 5 converse over the heavy conductors shown, including the wipers 21 and 22 of selector D and wipers 41 and 42 of connector H. After the conversation is completed the connection is released in the usual manner by 10 the hanging up of the receiver at the calling station which operation opens the circuit of the line relay 34 which in turn opens the trunk release holding circuits of relays 33 and 7 of the preceding switches and closes 15 the circuit of release magnet 80.

Let us assume now that the calling subscriber desires to set up a call to the subscriber whose line is located on the second contact of the second level of the second 20 bank of the connector instead of in the first bank. In this case it will be seen that it will be necessary to operate all the switches in exactly the same manner as when calling 222 except that the line circuit must be 25 switched from the lower to the second set of wipers. The called subscriber's number would therefore appear in the directory as 2B2. That is, just before the first set of impulses to the connector are sent the springs 30 2 and 3 will be operated automatically to switch over. The call will proceed as follows: The removal of the receiver causes the line switch C to operate to select an idle trunk which, we will again assume, leads to 35 the selector D. The calling device is then operated for the digit 2 as before to select an idle connector in the second group or level, such as H. The next digit being B the subscriber inserts a finger into the hole 40 so designated, and rotates it around to the finger stop. Just before the finger meets the stop, the springs 2 and 3 are operated to ground one side of the line circuit as shown at substation A. As the line circuit is now 45 connected in series with relays 34, 35 and 36 of the connector, this grounding of one side of the line causes one winding of relays 34 and 36 to be short circuited through ground. This has no effect on relay 34, but relay 36, 50 being differential, will now operate to close the springs 81 in the circuit of switching relay 50, which relay energizes and locks itself energized to ground on springs of relay 37. As soon as the finger is removed from the dial the springs 2 and 3 are again opened and the dial returns to deliver 55 two impulses, as when 2 is dialed, to the line relay 34. The switch is therefore operated two steps in a vertical direction by this digit, and when the next digit being 2 the rotary magnet is controlled by relay 34 in the same manner as when calling 222, to step the wipers 41-49 to the second set of contacts 60 in their respective banks. Now instead of the testing being controlled over the wiper 65

43 as in the previous call, the busy relay or wiper cut on relay is controlled over the private wiper 46, which is associated with the second bank, through spring 62 and its front contact and spring 63 and its back 70 contact. It will be seen therefore that only the line in the second bank will be tested and if idle, connection will be extended thereto over the wipers 44 and 45 which are now effective. Conversation may be carried 75 on in the usual manner over this connection and relay 50 will be released when the switch is released.

Let us assume now that the calling subscriber desires to call a party whose line is 80 located in the upper bank of the connector, whose number we will assume to be 2M2. In this case the call will again proceed in the same manner as when calling 222 except that just before sending the first digit to 85 the connector the springs 4 and 5 are operated by the subscriber to include the high resistance X at the substation in series with the line circuit. In this case the marginal relay 35 will be allowed to fall back instead 90 of pulling up with relay 36 as before, and a circuit will be closed for the switching relay 51 through the springs 82 and off normal springs 83. It will be seen the only time relays 50 and 51 may be energized is 95 before the switch steps off normal, so that no false switching may occur due to the fact that off normal springs 83 and 84 open on the first vertical step. Relay 51 now energizes, locks itself to ground at springs of 100 relay 37, and switches the line circuit to the upper set of wipers 47, 48 and 49. The switch will again be operated to step all wipers to the second contact in the second 105 level of their banks except that the testing will be controlled over private wiper 49 and the connection will be completed to the line in the upper bank, if idle, over wipers 47 and 48.

I have now described the different ways 110 that a subscriber may set up a call to any other subscriber whose line is located in that part of the exchange which is accessible to switches of the lower bank of the selector D. It will be understood that other 115 selectors, similar to D, may be inserted before the connector H without departing from the spirit of my invention, and that each selector or group of selectors added, increases the capacity a great deal, owing to 120 its 300 trunk capacity.

The trunk lines leading from the second and upper banks of the selector D may lead 125 to any desired points, either to long distance boards, other exchanges, or simply to other groups of connectors similar to H. That is, in the last instance, assuming the trunk lines in each bank lead to connectors such as that shown at H, then the selector D has access on each of its ten levels to three 130

groups of connector switches each group of connectors having access to 300 lines. Therefore the system as illustrated would have a capacity of 9,000 lines without further addition.

Assume now that the calling subscriber desires to call another subscriber which is accessible from one of the connector switches which is connected to the second level of the second bank of the selector D. If this line be located, for instance, in the second set of contacts in the second level of the second bank of this connector, then the directory number of such subscriber would be BB2. Now when the first digit B is called the springs 2 and 3 at substation A are closed for an instant just before the digit is sent, and, by grounding one side of the line, causes the differential relay 14 of selector D to energize to close a circuit for the switching relay 31 in the same manner that the relay 36 closes the circuit of the switching relay 50 of the switch H. Relay 31 locks itself energized and switches the line circuit to the second set of wipers 24, 25 and 26. Therefore as soon as the switch starts to rotate, only the wiper 26 being effective, an idle trunk line in the second level of the second bank will be selected and the connection will be extended to a connector H in that group. The second digit B now controls the selected connector in the same manner as the switch H (Fig. 2) was controlled when 2B2 was called, and the line on the second contact in the second level of the second bank of that connector will be seized.

Now, if the calling subscriber desires to call a party whose line is accessible to connector switches in some level of the third bank of selector D, then the digit would be for example MB2, and the relay 13 will be operated as was relay 35 of the connector H to control relay 30 of the selector D to switch the line circuit to the upper wipers. In this case therefore a trunk line located in the upper bank of the selector D will be selected.

It will be seen therefore that the system is divided into three large groups, as illustrated, that is, after seizing the selector D the subscriber may direct his call to three paths without any conscious action on his part. That is, if the first digit is any figure the call may be extended to any one of one hundred connectors as is now the practice. If the first digit dialed is any of the letters A to K then the call may be extended to any one of the 100 connectors in the second bank or in the second path, while if the first digit is any of the letters L to W then the call may be extended to the third path or subdivision over any one of the hundred connectors in the third bank of the switch. Further than this, after the subscriber has

determined over which path or into which subdivision his call will lead, he then has three more alternative paths or groups to select depending upon the first digit sent to the seized connector switch.

Therefore, if a line in the first sub-group is to be called the first digit will always be a figure, the second may be either letter or figure, and the last always a figure; that is, the called number may be 352, 3B2, 3R3, or any such combination. While if the call is to lead to the second subdivision then the first digit called will always be one of the letters A—K, that is, the number may be B22, BA2, or BR2, etc. Now, if the call goes to the third subdivision the first digit of the called number will always be one of the letters L—W in the outer concentric row of finger holes and the called number may be M22, MB2, or MN2, etc.

It will be seen therefore, that I have provided a very efficient and novel method of operating and constructing an automatic telephone system so that the capacity of such an exchange is greatly increased and so that the operations required of a subscriber are greatly reduced. Also it is thought that this peculiar method of designating a called subscriber's number will be very easy to remember and will be more pleasing to the subscribers than an all number system.

Having fully described and ascertained the objects and features of my invention, I will point out in the appended claims what I consider to be new and desire to have protected by Letters Patent.

What I claim is:

1. In a telephone system, an automatic switch, a plurality of wipers for said switch, trunk lines, a calling device having a pair of impulse springs for controlling said switch to connect said wipers simultaneously with different trunk lines, a dial for said device, a plurality of concentric rows of finger holes on said dial for variably controlling said impulse springs, the corresponding concentric holes of each row being arranged to control said impulse springs in a similar manner, a switching device controlled by said calling device when controlled by the holes of one row for switching from one to another of said wipers, and a switching device controlled by said calling device when controlled by the holes of another row for switching to another of said wipers.

2. In a telephone system, an automatic switch having a plurality of wipers, and a bank of contacts for each wiper, a calling device for controlling the operation of said switch, a plurality of controlling means for said calling device, one for each wiper, means whereby when the dial is operated through the medium of one controlling means, the switch is operated to extend a

- connection over one wiper, means whereby when the switch is operated by means of another controlling means of the dial, a connection is extended over another wiper, and 5 means whereby when the switch is operated by means of another of said controlling means the connection is extended over a third wiper.
3. In a telephone system, an automatic 10 switch, a plurality of groups of trunk lines accessible to said switch, a calling device associated with said switch, a dial having a plurality of rows of finger holes associated with said calling device for controlling the same to operate said switch, one of said rows being designated by numbers and others of said rows being designated by letters, means controlled by the numbered 15 row for operating said switch to extend a connection to a trunk line in one group only, and means controlled by each of the lettered rows for extending a connection to other groups.
4. In a telephone system, an automatic 20 switch, a pair of wipers for said switch mounted on a common shaft, a calling device, a row of numbered finger holes for controlling said calling device, a row of lettered finger holes for controlling said device, means controlled by said calling device when operated through the medium of said 25 rows for operating said switch to extend a connection over either wiper, the wiper over which the connection is extended depending upon the row used.
5. In a telephone system, an automatic 30 switch, a plurality of groups of trunk lines accessible thereto, a calling device, a plurality of controlling means for said device, each adapted to control said calling device to operate said switch through a similar movement, means associated with one of said controlling means for directing the extended connection to a trunk line in a first 35 group when the switch is operated through the medium of said one means, means associated with another controlling means for directing the connection to a trunk line in a second group only, and means associated 40 with another of said controlling means for directing the connection to a trunk line in a third group of lines.
6. In a telephone system, an automatic 45 switch, a line leading to said switch, a plurality of wipers associated with said switch, a calling device associated with said line for operating said switch, a row of numbered finger holes for controlling said device, a plurality of rows of lettered finger 50 holes for controlling said device, means whereby when the device is controlled through the medium of the numbered row to operate the switch, the line is connected 55 to one of said wipers, and means associated with said lettered rows for connecting the 60 line to others of said wipers.
7. In a telephone system, an automatic 65 switch having a definite movement, a plurality of groups of trunk lines accessible to said switch at any point in its movement, a calling device, a row of numbered holes and a row of lettered holes each for controlling the device to step the switch to any point in its movement, and means dependent upon the row used for determining the group into 70 which the connection is to be extended.
8. In a telephone system, an automatic 75 switch having a plurality of wipers, a line leading to said switch, a plurality of groups of trunk lines accessible to said switch, a calling device for operating said switch to connect each of said wipers simultaneously with a trunk line in a separate group, a numbered and a lettered row of finger holes for said device, and means associated with 80 each row for connecting said line to a different one of said wipers when the device is controlled through the medium of the associated dial.
9. In a telephone system, an automatic 85 switch having a definite movement, a line leading to said switch, a plurality of wipers associated with said switch, a calling device associated with said line, a numbered and a lettered set of finger holes for controlling 90 said device to step said switch to any point in its movement, and means dependent upon which set is used for switching the line to a predetermined one of said wipers.
10. In a telephone system, an automatic 95 switch, a line leading to said switch, a plurality of wipers for said switch, one of said wipers being normally connected to said line, a calling device for said line, a plurality of rows of controlling holes for said 100 device for operating the same to control the operation of said switch, means controlled when one row is used to operate the dial for switching the line from the normally connected wiper to another, and means controlled when another row is used to operate the switch for switching the line to still another of said wipers.
11. In a telephone system, an automatic 105 switch, a line leading to said switch, a plurality of wipers for said switch for extending connections from said line, one of said wipers normally connected to said line, a calling device for said line for operating 110 said switch, a numbered and a lettered row of finger holes for controlling said device, means controlled by the numbered holes when used to operate the device for causing the operation of the switch to extend connection only over the normally connected 115 wiper, and means controlled by the lettered 120 holes for controlling the device for causing the operation of the switch to extend connection only over the normally connected wiper, and means controlled by the lettered 125 holes for controlling the device for causing the operation of the switch to extend connection only over the normally connected wiper.

holes for causing the operation of the switch to extend connections over another of said wipers only.

12. In a telephone system, an automatic switch, trunk lines accessible to said switch divided into groups, a calling device, a numbered row of holes and a plurality of rows of lettered holes, each row having means for controlling said device to operate said switch to connect with a trunk line in each group simultaneously, and means associated with each row for extending a connection to a trunk in only one group, the group depending upon the row used.

13. In a telephone system, an automatic switch, a line leading to said switch, a plurality of wipers for said switch, a single operating magnet for moving all of said wipers simultaneously, a line relay for operating said switch, a calling device having a plurality of controlling sets of finger holes for controlling said line relay to operate said switch to extend a connection over a predetermined one of said wipers, the wiper used depending upon the set of holes used to control the device.

14. In a telephone system, an automatic switch, a line leading to said switch, a plurality of wipers for said switch, a line relay for controlling said switch to extend a connection from said line over any of said wipers, a pair of switching devices for connecting said line to alternate wipers, a calling device associated with said line for operating said switch, a pair of controlling devices for said dial, and means for automatically operating either of said controlling devices during the operation of said calling device to switch the line to any wiper.

15. In a telephone system, an automatic switch having a plurality of wipers, a line leading to said switch, a calling device having means for controlling said line to operate said switch, a differential relay for connecting the line to one of said wipers, a marginal relay for connecting the line to another of said wipers, and automatic means controlled in the operation of said calling device for controlling either of said relays to switch to any desired wiper.

16. In a telephone system, an automatic switch, a line leading to said switch, a plurality of wipers for said switch, a calling device for operating said switch to extend a connection over any of said wipers, relays for switching said line to any of said wipers, means controlled by the operation of said device when controlled in one manner to ground one side of the line to switch said line to one of said wipers through the medium of one of said relays, and means controlled by the device when controlled in another manner for including a resistance in said line to switch the line to another

wiper through the medium of another of said relays.

17. In a telephone system, an automatic switch, a line leading to said switch, a wiper for said switch normally connected to said line, other wipers for said switch, a marginal relay for switching said line to one of said other wipers, a differential relay for switching the line to another of said other wipers, a calling device for controlling the operation of said switch, and means controlled by said calling device for energizing either of said relays to switch the line to a predetermined one of said wipers.

18. In a telephone system, an automatic switch, a plurality of trunk lines accessible to said switch, a line leading to said switch, impulse springs for controlling said line circuit to operate said switch to connect with any of said trunk lines, another pair of springs associated with said line adapted to limit the connection from the switch to certain of said trunk lines, a third pair of springs associated with said line for limiting the connection from the switch to certain other of said trunk lines, and automatic means individual to said calling device for controlling said impulse springs and either of said other pair of springs at will.

19. In a telephone system, subscribers' lines arranged in groups, a plurality of automatic switches, a calling device for controlling the operation of any of said switches to extend a connection from a calling line to a line in any of said groups, a dial for controlling the operation of said device, having finger holes in a plurality of rows, one row designated by numbers and other rows designated by letters, whereby the said dial may be operated in accordance with a called subscriber's number which consists of letters and numbers, and means associated with the dial whereby if the dial is operated by means of the numbered row of holes only the call may pass only to a line in one group, if the dial is operated by means of one lettered row only, the call may be extended to a line in a second group only, and if the dial is operated by means of another lettered row only, the call may be extended to a line in a third group only.

20. In a telephone system, subscribers' lines arranged in groups, a plurality of automatic switches, a calling device for controlling the operation of any of said switches to extend a connection from a calling line to a line in any of said groups, a dial for controlling the operation of said device, having finger holes in a plurality of rows, one row designated by numbers and other rows designated by letters, whereby the said dial may be operated in accordance with a called subscriber's number which consists of letters and numbers, means associated with the dial whereby if the dial is operated by means of

the numbered row of holes only the call may pass only to a line in one group, if the dial is operated by means of one lettered row only the call may extend to a line in a second group only, and if the dial is operated by means of another lettered row only, the call may be extended only to a line in a third group, and means whereby if the dial is operated in accordance with a called number 10 consisting of both letters and figures the call may be extended to a line in one of a number of other groups, the group into which the call may extend depending upon the order in which said letters and figures are dialed.

21. In a telephone system, an automatic switch, three sets of wipers for said switch, a calling device for controlling said switch in accordance with the digits of a called 20 number, and means controlled by a single operation of said calling device for first electing one of said sets of wipers and for then moving said wipers to a desired position.

22. In a telephone system, an automatic switch, a plurality of wipers for said switch, a calling device associated with the switch and having two rows of finger holes for controlling the device, each row having 30 means associated therewith for switching to an alternate set of the wipers, and for then sending the proper impulses of a digit to the switch to move the wipers.

23. In a telephone system, an automatic switch having a plurality of wipers, a line leading to said switch, a calling device for the line for controlling the switch to extend connections, a plurality of sets of finger holes for the dial, said holes so arranged 40 that any set may be used to operate the calling device to send impulses in accordance with a digit of the called number, means associated with one of said sets and operative when that set is used to operate the device for switching said line to one alternate set of said wipers, and means associated with another set for switching the line to another alternate set of said wipers when that set is used to send a digit.

24. In a telephone system, an automatic switch, three sets of wipers for the switch each having access to a different group of lines, a calling device for controlling said switch, said device having a plurality of 55 rows of controlling finger holes, means controlled by a single operation of the calling device when controlled by one of said sets of holes for first electing a set of wipers and then moving said wipers to a sub group in its particular group, and means controlled by a single operation of the dial when controlled by another of the sets for electing another set of wipers and then moving them to the sub group.

25. In a telephone system, an automatic

switch, a pair of wipers for said switch, trunk lines associated with each wiper, a calling device, impulse springs for said device, a finger hole dial for variably controlling said impulse springs to operate said 70 switch having a pair of concentric rows of finger holes, the corresponding holes of each row adapted to operate said impulse springs a like number of times, means whereby when the switch is controlled through the medium of one row of holes, a trunk will be connected with over one of said wipers, and if the switch is operated through the medium of the other row of holes a trunk will be connected with over the other wiper.

26. In a telephone system, a series of automatic switches each having a pair of wipers, a calling device, impulse springs controlled by said calling device, a finger hole dial for said device having a pair of rows of finger 85 holes, the corresponding holes of said rows adapted to control said impulse springs to operate said automatic switch in a like manner, and means depending upon the row in which the finger hole used is located for determining over which wiper a connection is extended.

27. In a telephone system, an automatic switch, a pair of wipers for said switch each having a plurality of trunk lines accessible 95 thereto to which it is adapted to extend a connection, a calling device for controlling the operation of said switch, a dial for controlling said calling device, a pair of rows of finger holes for said dial, each row corresponding to one of said wipers, and circuit arrangements whereby when the dial is operated to control said switch through the medium of one of said rows a connection will be extended only to a trunk line accessible to one wiper and when the other row is used a connection will be extended only to a trunk accessible to the other wiper.

28. In a telephone system, a calling device including a pair of impulse springs, a circuit for said impulse springs, an automatic switch controlled over said circuit, trunk lines accessible to said switch divided into groups, a finger hole dial for said device having a pair of concentric rows of finger holes, said holes arranged in pairs so that the holes of each pair when used to operate the impulse springs have a similar effect upon said springs, another pair of springs controlled in common by the use of any finger hole in one row, and means whereby when one of said rows of holes are used the automatic switch is operated to select a trunk line of one group, and when the other row of holes are used the automatic switch is operated to select a trunk line in another group through the medium of said other pair of springs, the group in which a trunk line is to be selected being predetermined before the switch is operated.

29. In a telephone system, a series of automatic selector switches, an automatic connector switch, said selectors and said connector operated successively to extend a connection to a called line, a pair of wipers for each switch, each having access to a different group of lines, a calling device for controlling said switches, a pair of rows of finger holes for controlling the operation of said device, impulse springs controlled in common by any of said holes to operate the switches, an additional pair of springs controlled by one of said rows of holes to switch the connection from one wiper to another, whereby when the device is operated by means of one of said rows the connection is extended over one wiper of each switch, and when the dial is operated by means of the other row, the connection is extended over the other wiper of each switch. 35
- 5 10 15 20
30. In a telephone system, an automatic switch having a definite motion in two planes, a pair of wipers for said switch, a calling device, a pair of groups of finger holes for said device, impulse springs controlled in the same manner by the corresponding holes in each group to operate said switch, a device controlled by the calling device only when one of said groups of holes are used to switch a connection from one wiper to the other, whereby when said impulse springs are operated by said device through the medium of any hole in one row the connection is extended over one wiper. 40 45 50 55 60 65
